UNITED STATES PATENT OFFICE.

FRANCIS M. UNDERHILL, OF NEW YORK, N. Y., ASSIGNOR TO WHITALL
TATUM & CO., OF SAME PLACE.

DESIGN FOR A DRUGGIST'S SHOW-BOTTLE.

SPECIFICATION forming part of Design No. 20,836, dated June 16, 1891.

Application filed May 11, 1891. Serial No. 392,396. Term of patent 14 years.

To all whom it may concern:

Be it known that I, FRANCIS M. UNDERHILL, a citizen of the United States, residing at New York, in the county and State of New York, have invented and produced a new and original Design for Druggists' Show-Bottles, of which the following is a specification.

This invention relates to the new configuration and ornamentation of a suspended druggist's show-bottle; and it consists of the new shape constituting the entire bottle, as hereinafter described.

The accompanying drawing, forming a part hereof, represents a side view of the design for a druggist's show-bottle.

A is the central body of the bottle. The lower ornament B has a cup-shaped top a, as shown. From the center of this cup a hangs

an ornamental pendant b. Curved arms d extend from the lower ornament B to the top ornament D of said bottle. This top ornament is composed of a flaring mouth e or upper portion and of a hood-like outwardly-extending lower portion f, a concave neck-band g being between the parts e and f. The entire bottle is represented as suspended from an ornamental bracket E.

What I claim is—

The design for a show-bottle, the same consisting of the body A, lower ornament B, upper ornament D, and intervening curved bands d, substantially as shown.

FRANCIS M. UNDERHILL.
